UNITED STATES PATENT OFFICE

DANIEL C. ROBERTS, OF TRENTON, NEW JERSEY

AEROPLANE

Application filed March 17, 1930. Serial No. 436,572.

This invention appertains to aeronautics and more particularly to a novel and improved aeroplane and glider construction. One of the primary objects of my invention is to provide a novel sustaining wing extending the full length of the aeroplane fuselage of a substantially hexagonal shape in plan embodying a transversely extending front leading edge and a transversely extending rear trailing edge with oppositely inclined front and rear leading and trailing edges extending from said first mentioned edges.

Another important object of my invention is the provision of vertical wing or lateral surfaces depending from the wings and arranged on opposite sides of the fuselage forming an efficient means for sustaining the aeroplane in flight against side slip and facilitating the banking and turning of the aeroplane.

A further object of my invention is the provision of a novel vane carried by the vertical side wing or surfaces below the fuselage mounted on a horizontal pivot and capable of movement to a vertical position below the vertical wing faces and between the fuselage and said vertical wing faces to form an efficient air brake to lessen the speed of the aeroplane in the air and to facilitate the landing thereof in a small landing field, the vane also forming an efficient means for permitting the gaining of altitude during the take-off of the aeroplane, said vane being adapted to be disposed at an angle to the horizontal to facilitate the climbing of the aeroplane.

A further object of my invention is the provision of a novel wing, vane and side vertical faces for an aeroplane, which can be used with any preferred type of fuselage, thereby allowing the conventional type of fuselage to be used with the aeroplane.

A further object of my invention is to increase the safety in the flying of aeroplanes and render the usual aeroplane of a stronger and sturdier design.

A still further object of my invention is to provide an improved aeroplane of the above character, which will be durable and

efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:

Figure 1 is a side elevation of my improved aeroplane.

Figure 2 is a top plan view of the same.

Figure 3 is a front elevation of my aeroplane.

Figure 4 is a bottom plan view of the same.

Figure 5 is a transversely sectional view through the improved plane taken on the line 5—5 of Figure 1 looking in the direction of the arrows.

Referring to the drawings in detail, where in similar reference characters designate corresponding parts throughout the several views, the letter A generally indicates my improved aeroplane which comprises a longitudinally extending fuselage 10 which may be of the usual or any preferred shape and construction forming the support for the engine, pilot seat and the like. The front of the fuselage may carry the usual or any preferred type of tractor propeller 11.

Connected with the fuselage 10 in any preferred way is my improved wing or sustaining surface 15, which forms an important part of my present invention. In the present showing I have illustrated a single wing or in other words a monoplane, but it is to be understood that two or more wings can be utilized without departing from the spirit or the scope of my invention to provide a biplane or a triplane.

Likewise, if desired, this wing can be of a hollow construction to form a reservoir or tank for fuel or the like or as means for receiving a lighter than air gas.

In accordance with my invention the wing 15 extends the full length of or substantially the full length of the fuselage 10 and is of a substantially hexagonal shape in plan embodying a straight transversely extending

front leading edge 16, a straight transversely extending rear trailing edge 17, front inclined side leading edges 18, and rear inwardly inclined trailing edges 19. Thus, 5 while it can be seen that I have provided an aeroplane with a relatively large wing spread, the same is so constructed as to form an efficient means for cutting through the air.

Likewise, in accordance with my invention 19 I provide spaced parallel longitudinally extending vertically disposed wing surfaces 20 and 21 which are arranged on opposite sides of the fuselage 10 in spaced parallel relation thereto. These lateral or vertical wing surfaces 5 faces 20 and 21 may likewise extend the full length of the fuselage; if desired; but the same preferably taper rearwardly to the tail of the fuselage.

In order to provide efficient means for supporting and strengthening the side lateral or vertical wing surfaces 20 and 21, I can provide upper and lower longitudinals or spars 22 and 23, the upper longitudinals being connected to the wing 15 to form a brace therefor. Likewise a transversely extending main spar 24 can be provided which extends across the upper longitudinal spars 22 and has its terminals connected to the wing tips. The front and rear longitudinal spars 22 and 23 25 can be connected together by transverse brace bars 25 and vertical uprights or standards 26. Likewise diagonal braces 27 may lead from the longitudinal spars to the fuselage 10. I also can provide brace bars 27' for the wing 30 tips and these brace bars can lead to the wing tips through the longitudinal spars 23. The provision of the side lateral or vertical wings 20 and 21 forms another salient part 35 of my invention, as by the use of these side lateral surfaces I am enabled to facilitate the even travel of the aeroplane through the air and to permit the efficient turning of the aeroplane in the air.

The aeroplane may be provided with any 40 preferred type of landing gear either for ground or water and in the present instance I have shown the lower longitudinal spars 23 adjacent to the forward ends thereof provided with ground wheels 28. Likewise a longitudinally extending tail skid 29 is provided, and it is to be noted that this tail skid 50 extends a material distance forwardly from the rear tip of the fuselage and is covered to provide a depending fin 30. The rear end of 55 the fuselage can likewise support the usual tailpieces 31 which may embody the vertical and horizontal rudders and stabilizers.

Forming another and salient feature of 60 my invention is the front transversely extending vane 35 and this vane is so constructed and arranged as to constitute both a lifting surface, when in one of its positions and as a wind break when in another one of its 65 positions.

65 This vane 35 extends between and entirely

across the lateral side or vertical wings 20 and 21 and a horizontal pivot 36 is provided therefor which pivot is carried by the lower longitudinal spars 23. The pivot is located substantially equally distant the front and rear edges of the vane, as clearly shown in Figure 2 of the drawings. Any desired means can be provided for operating the vane 35, such as a hand lever secured to the pivot 36 extending into the fuselage through a suitable slot formed thereon. The hand lever can carry a pawl for locking engagement with a segmental rack secured to the fuselage. 70

In use of the vane, when it is desired to take off from a field or to gain altitude the vane is set at an angle to the horizontal inclining upwardly toward the front of the aeroplane. This provides a lifting surface and permits the quick gaining of altitude by 80 the aeroplane.

When it is desired to lessen the forward speed of the aeroplane in landing and the like the rear edge of the vane 35 is swung upwardly so that the vane will occupy a substantially vertical position with the rear edges thereof in contact with the lower surface of the wing 15. The rear edge of the vane is cut away as at 37 so that the vane will fit about the fuselage when the same is swung to its vertical position and this cut out portion 37 provides side tail extensions 38 which lie in between the fuselage and the side lateral or vertical wings 20 and 21 to prevent the passage of air through the aeroplane between the fuselage and said wings 20 and 21. By 90 this arrangement the vane will act as an efficient air break and stop the forward travel of the aeroplane. Thus it can be seen that I have provided an aeroplane which can land in an exceedingly restricted area. 95

The aeroplane and its various parts can be constructed from any desired type of material such as all wood, all metal, or a combination of wood, metal and fabric. In fact any desired material and arrangement can be 100 used.

In reducing my invention to practice, various minor changes in the details of construction may be necessary, but without sacrificing any of the advantages of my invention, as defined in the appended claims. 115

What I claim as new is:

1. In an aeroplane, a longitudinally extending fuselage, a sustaining wing connected with the fuselage and extending substantially the full length thereof, longitudinally extending vertically disposed wings secured to and depending from the sustaining wing on opposite sides of the fuselage in spaced relation thereto, a vane arranged between the vertical wings, a horizontal pivot for said vane arranged intermediate the ends thereof, whereby said vane can be swung to a vertical position or at an angle to the vertical and to 120

125

130

135

the horizontal, and means for operating said vane.

2. In an aeroplane, a longitudinally extending fuselage, a sustaining wing connected with the fuselage and extending substantially the full length thereof, longitudinally extending vertically disposed wings secured to and depending from the sustaining wing on opposite sides of the fuselage in spaced relation thereto, a vane arranged between the vertical wings, a horizontal pivot for said vane arranged intermediate the ends thereof, whereby said vane can be swung to a vertical position or at an angle to the vertical and to the horizontal, means for operating said vane, the rear end of said vane being notched for receiving the fuselage when the vane is swung to a vertical position, the notch defining side pieces for lying between the fuselage and the vertical wings and for engaging the sustaining wing.

In testimony whereof I affix my signature.
